UNITED STATES PATENT OFFICE

CUYLER S. MCCHESNEY, OF KENMORE, NEW YORK, ASSIGNOR TO DUNLOP TIRE AND RUBBER CORPORATION, OF BUFFALO, NEW YORK, A CORPORATION OF NEW YORK

GOLF BALL WINDING MACHINE

Application filed July 23, 1930. Serial No. 469,996.

My present invention relates to a machine for winding a small rubber center with rubber thread to form the body of a golf ball.

The objects of the invention are to provide a machine in which a number of balls may be wound simultaneously and in which the winding of each ball is individually controlled; to provide mechanisms whereby the rubber thread with which the center is being wound is automatically severed and the winding stopped when the golf ball has attained the required diameter; to provide a multiple winding apparatus in which the centers to be wound may be individually inserted without interrupting or stopping the winding of other centers; and to provide a multiple winding mechanism in which the balls are wound between pairs of eccentrically set rotating discs driven at different speeds and in which the driving of each pair of discs is pneumatically controlled by the distance apart of its respective discs.

A further object is to provide a machine for winding a soft center or paste center golf ball and in which the initial windings are accomplished with a thread under a low tension or without tension, and in which the tension is automatically increased when the windings have reached a determined diameter.

With these and other objects in view which will appear from the following description, the invention comprises the winding machine and mechanisms described in the following specification.

The various features of the invention are illustrated in the accompanying drawings in which—

Fig. 1 is a plan view of a winding machine and control mechanism embodying a preferred form of the invention.

Fig. 2 is a front elevation of the mechanism shown in Fig. 1.

Fig. 3 is a side elevation of the machine taken from the left of Fig. 1.

Fig. 4 is a longitudinal sectional view of a portion of the machine showing the winding disc driving mechanism and pneumatic control.

Fig. 5 is a vertical sectional view of a portion of the machine taken on line 5—5 of Fig. 6.

Fig. 6 is a longitudinal sectional view taken on a horizontal plane through one of the winding elements.

Fig. 7 is a vertical elevation partly in section of a part of the machine showing the winding mechanisms.

Fig. 8 is a vertical sectional view of a portion of the machine taken on line 8—8 of Fig. 6.

Fig. 9 is a perspective view of a mechanism for separating the winding discs to permit the insertion of a new center.

Figs. 10 and 11 are, respectively, longitudinal sectional and face views of one of the winding discs.

Fig. 12 is a diagram of the apparatus for severing the thread and for controlling the driving of the winding discs.

Figs. 13 and 14 are, respectively, enlarged detail vertical sectional and elevation views of the thread severing elements.

Fig. 15 is a detail sectional view showing the automatic tension control mechanism.

In my invention an end of a rubber thread is attached to a small rubber center on which it is to be wound and this center is then placed between a pair of spaced discs having on their opposite faces complementary grooves or depressions of annular shape. These discs are rotated about their centers but the centers are out of alignment or eccentric one to the other and the discs are rotated at somewhat different speeds so that the center and its windings are rotated in a constantly varying manner so that the windings are sufficiently varied or haphazard

to form a spherical ball. The discs are pressed towards each other by resiliently act-

ing means which permit them to spread apart as the ball and its windings increase in diameter. When the ball has attained the desired diameter the discs will have been separated to such a distance as to set into operation the means for severing the thread and for stopping the further rotation of the individual discs between which the ball is being wound.

- 10 In the preferred form of the invention the severing means comprises a wire over which the thread passes and which may be heated by means of an electric circuit to a temperature sufficient to soften or melt the rubber of the thread. This current is controlled by a switch which is in turn operated by the separation of the winding discs. The severing of the thread serves to actuate a pneumatic clutch control means which thereupon disconnects the individual disc driving mechanism from a central or common driving means. The disc may be then separated by a mechanical control mechanism and the wound ball removed and replaced by a new center to be wound. A number of individual winding discs may thus be driven from a common source, each being individually and automatically controlled independently of each of the others.
- 20 30 In the accompanying drawings the invention is illustrated by way of example as applied to a machine having six sets of winding discs and controlling means. It will be understood, however, that any number of sets of winding discs and mechanisms may be employed.

As certain of the elements of each of the winding discs and driving means therefor are identical, common reference numerals are used in the accompanying drawings for the elements of each set, and the description of one of these winding elements will be sufficient for all.

Referring more particularly to the accompanying drawings, the sets of winding discs are arranged in two vertical groups of three winding sets each. A small rubber center is placed between a pair of discs 20 and 21 and one end of a rubber thread 22 that is to be wound on the center is drawn from a spool 23, then through a tension mechanism 24 to the center on which it is wound to form the ball 25.

The discs 20 and 21 have a rubber face 26 having an annular groove 27 as shown in detail in Figs. 10 and 11. The faces 26 of the discs 20 and 21 are opposed to each other and the grooves 27 are so positioned as to be but slightly eccentric one to the other and to accommodate or receive the center of the ball 25 between the two grooves. The grooves 27 have a radial section of a rounded or circular segment shape.

The face 26 carrying the groove 27 of the winding disc 20 is secured on a back 28 which

is in turn adjustably mounted on a radial flange 29 of a rotating spindle or shaft 30. Similarly the disc 21 is mounted on the end flange 31 of a shaft 32. The shafts 30 and 32 are rotated in the same direction thus causing the thread 22 to wind on the ball 25, but are rotated at different speeds thus causing the ball to rotate in a direction other than that of the shafts 30 and 32.

To prevent a steady and uniform turning of the ball 25 in a direction other than that of the winding on direction, the discs 20 and 21 are adjusted on the flanges 29 and 31 respectively, so that the centers of the grooves 27 are slightly offset or eccentric to each other. For this purpose the flange 29 or 30 is provided with a diametrical rib 33 which fits into a similar recess in the backing 28, and the backing 28 is secured to the flange 29 by means of screws 34 that pass through elongated slots 35 in the flange 29 and thus, upon being loosened, permit the backing 28 to be moved lengthwise of the rib 33 to a desired position and then tightened. As a result of this eccentricity the ball 25 is not only rotated in a direction to wind the thread 2, but is rotated on constantly and erratically shifting axes to distribute the thread uniformly throughout the surface of the ball and thus builds up an entirely symmetrical spherical winding.

The shafts 30 and 32 are rotatably and slidably supported in bearings, preferably ball bearings 36, 37 and 38, 39 respectively, in a common frame 40. The shafts 30 and 32, and with them the discs 20 and 21, are pressed toward each other, sliding in their respective bearings, by a resiliently acting means such as the weight 41 acting through a suitable linkage as shown in perspective in Fig. 9. In this mechanism the weight 41 is suspended by a rod or link 42 from one arm 43 of a double bell crank lever 44. An arm 45 of the bell crank lever 44 is connected through a link 46 to one end of a crank 47 mounted on a cross shaft 48. Also rigidly mounted on the shaft 48 is a yoke 49 having opposed pins 50 which, as shown in Fig. 6, bear against a thrust bearing 51 secured to the shaft 30 by means of a collar 52.

Similarly, a lever arm 53 of the double bell crank 44 and on the opposite side of the bell crank is connected by means of a link 54 to a crank 55 on a cross shaft 56 which acts on the shaft 32 through a yoke and a thrust bearing, not shown, similar to that of the shaft 30. As is apparent from Fig. 9, the weight 41 acts to shift or urge the shafts 30 and 32 of the discs 20 and 21 toward each other thus holding the ball 25 firmly in the space between the grooves 27 of the discs 20 and 21. In order to insert the center between the discs 20 and 21 in setting the machine for operation, the double bell crank lever 44 is rotated against the action of the weight 41

by means of a pedal 58 which is connected by means of a link 59 to one end of a fourth arm 60 of the double bell crank 44. When the pedal 58 is depressed the double bell crank 5 44, shaft 56 and yoke 57 are rotated counter clockwise, and the shaft 48 and yoke 49 are rotated clockwise to draw the shafts 30 and 32 and the discs 20 and 21 away from each other. When the center and its initial 10 windings have been placed between the discs 20 and 21 the pedal 58 is released and the weight 41 rotates the shafts and yokes in reverse direction to press the discs 20 and 21 toward each other. As the diameter of the 15 ball 25 increases, the discs 20 and 21 separate proportionately thus rotating the shafts 56 and 46 of the double bell crank 44 to lift the weight 41. The extent of rotation of the shaft 56 and consequently, the extent of the 20 separation of the discs 20 and 21, is indicated by a pointer 61 secured on the end of the shaft 56 and moving over a scale 62, Fig. 7.

The rotation of the shafts 30 and 32 of each set of winding discs is driven from a 25 motor 63, Fig. 3, connected through a suitable transmission mechanism such as a belt or chain 64 to a pulley, sprocket or gear 65 on a main shaft 66, Figs. 3, 4 and 5. Rigidly mounted on the shaft 66 are gears 67, there 30 being one gear for each vertical tier or row of sets of winding discs. There are thus two gears 68 in the embodiment shown in the drawings. Each of the gears 67 meshes with and drives the lowermost of a set of gears 68, 35 one for each set of winding discs and interconnected by means of intermediate idler pinions 69 set in an extension 70 of the frame 40. Thus all of the gears 68 are driven simultaneously in the same direction from the 40 common drive shaft 66. The shaft 66 is suitably supported in bearings 71 and 72 mounted in a web 73 of the frame 40. Each of the 45 gears 68 is rotatably mounted by means of bushings 74 on a shaft 75 that is supported in bearings 76 in the frame 40 and is parallel to the shafts 30 and 32. There is one shaft 75 for each set of winding discs. The 50 gears 68 are freely rotatable on and relative to the shaft 75, but may be rigidly clutched thereto by means of a clutch 77 slidably keyed on the shaft 75 and having a clutch disc 78 adapted to engage a side face of the gear 68. When the clutch 77 is shifted on the shaft 75 to a position to cause the clutch disc 78 to engage the gear 68, the shaft 75 of the respective winding set is rotated and driven from the common drive shaft 66 through the gear 67 and its respective driving gear 68.

60 Keyed onto the shaft 75 are a pair of gears 79 and 80 which mesh respectively with gears 81 and 82 slidably keyed to the shafts 30 and 32 respectively between their respective bearings 36, 37 and 38, 39. It will thus be apparent 65 that the shafts 30 and 32 are driven in

the same direction from the common shaft 75. The gear ratios of the gears 79-81 and 80-82 are however, different so that the shafts or spindles 30 or 32 are driven at different speeds. For example, as shown in Fig. 6, the gear 79 has a smaller diameter than the gear 80 and the gear 81 has a larger diameter than the gear 82 so that the shaft 32 is driven at a greater speed than the shaft 30.

The clutch 77 is brought into and out of engagement with the gear 68 so as to connect and disconnect the shaft 75 from the gear 68 by pneumatically actuated means. When the clutch is to be moved, to the right in Fig. 6, to cause its friction disc 78 to engage the side face of the gear 68, air under pressure is admitted from an air valve assembly 83, Fig. 2, there being two such tanks shown in the present embodiment, through a pipe 84, one for each unit and thence through an individual 80 valve 85, Fig. 12, associated with the tensioning device 24 and a pipe 86 to the outer face of a diaphragm 87, Figs. 1, 6 and 12. The diaphragm is clamped at its edges between the end of the frame extension 70 and a cover 90 plate 88 forming with the latter a narrow chamber 89 in which the air received through the pipe 86 is confined. The pressure of the air within the chamber 89 forces the diaphragm 87 in a direction towards its respective clutch and gear 68, that is, towards the right in the position illustrated in Figs. 6 and 12. This thrust of the diaphragm is transmitted through a non-rotating head 90 and through a thrust bearing 91 to the outer 100 end of the clutch 77.

The clutch 77 is thus moved to bring its friction disc 78 into frictional engagement with the gear 68, thus clutching the latter to the shaft 75. The admission of air under pressure through the pipe 86 to the diaphragm chamber 89 of any of the individual winding units serves to clutch the drive shaft 75 of such unit to its respective driving gear 68.

When the ball 25 has attained the desired size, the valve 85 is closed and a valve 92 is opened, which connects a branch pipe 93 from the pipe 86 to a pipe 94 open to the atmosphere, thereby releasing the pressure in the pipe 86 and connecting the respective diaphragm chamber 89 to atmosphere. Thereupon the head 90 and diaphragm 87 are moved in a direction away from the respective gears 68 by means of a series of 100 springs 95 confined between an internal flange 96 of the frame extension 70 and recesses 97 in the head 90. The springs 95 are retained in position between the recesses 97 and pins 98 projecting thereinto from the 105 flange 96. The movement of the head 90 thus relieves the pressure of the clutch 77 against the gear 68 and disengages the shaft 75 from the latter.

The position of the valves 85 and 92 is 110

controlled by the tensioning device 24 in such a manner that when a rubber thread 22 is passing under tension to the ball 25 being wound, it lifts the outer arm 95' of a lever, 5 the other arm 96' of which extends between the opposite ends of valve actuating stems 97' and 98 for the respective valves 85 and 92, as shown in Fig. 12.

Thus when the arm 95' is maintained in its 10 raised position by the tension of the passing thread 22 the opposite arm 96' depresses and opens the valve 85 and closes the valve 92, and when the arm 95' drops, due to the severing of the thread 22, the arm 96' raises the 15 stem 98, opening the valve 92 and permitting the stem 97' to rise and the valve 85 to close.

It will be understood that the proper tension in the thread 22 to cause it to wind with sufficient tightness and tension on the ball 25 20 and to maintain the lever arm 95 in raised position may be accomplished by any suitable means. In the embodiment shown in the drawings this is accomplished by passing the thread from its respective spool 23 through a guiding eyelet 99, Figs. 1, 13 and 14, thence counter-clockwise about a tensioning drum 100, then under the outer arm 95 and clockwise about a second tensioning drum 101 and over a guide plate 102, Fig. 2, 25 to the ball 25. The rotation of the tensioning drums 100 and 101 is in each instance retarded by means of a friction disc 102 pressed towards the respective drum 100 or 101 by means of a spring 103 confined between the disc 102 and an adjustable nut 104. The position of the nut 104 relative to the disc 102 30 is adjusted to give any desired pressure by threading in one or the other direction on a rod 105 extending axially through the drum 100 or 101. The severing of the thread 22 is 35 automatically accomplished, when the ball 25 attains the desired size, by means of an electric heating element 106, Fig. 12, in contact with the passing thread and heated by an 40 electric circuit, the closing of which is controlled by the rotation of the respective yoke shaft 48 or 56 of the individual winding set.

The heating element 106 may comprise an exposed wire positioned at any suitable place 45 between the spool 23 and the ball 25, as for example, on the guide plate 102. Current for heating the wire 106 is taken from a main 107 through a branch wire 108 and thence through a mercury switch 109 to a wire 110 connected 50 at its end to the wire 106 and thence returns through a return wire 111 to a return main 112. The mercury switch 109 is mounted on an arm 113 secured to a collar 114 which is 55 in turn fixed on the yoke shaft 48 as indicated in Fig. 9. When the ball 25 is started and until it attains the desired diameter, the shaft 48 is in such a position that the arm 113 points obliquely downwardly. Consequently the 60 mercury 115 in the switch 109, flowing to the lowermost end, exposes and disconnects the

ends of the wires 108 and 110. As the ball 25 increases in diameter, separating the discs 20 and 21, it rotates the shaft 48 in a clockwise direction and tilts the arm 113 and the switch 109 to an upwardly inclined position as shown in Fig. 12, and thus connects the wires 108 and 110 and throws the heating element 106 in circuit between the mains 107 and 112. Further winding of the ball is thereupon stopped as described above. To prevent the 70 continued heating of the wire 106 after the winding has been discontinued, a pneumatically operated switch 116 is inserted in the wire 111 and is connected to and controlled by the pressure in the pipe 86 to open the switch when the pressure falls. The ball 25 may then be removed and replaced by a new center and the winding again started. As the new center will have a less diameter than that of the completed ball, the mercury switch 109 will return to open position. 75

When the tension on the thread 22 lifts the lever arm 95' and admits air under pressure to the pipe 86, it again closes the pneumatically operated switch 116 so that the heating element 106 will again sever the thread 22 when the mercoid switch 115 is tilted so as to close the circuit. 80

When the machine is to be used for winding elastic thread on a soft rubber or paste 85 center the initial windings are done with a thread under a slight or negligible tension in order to prevent the ball from being distorted and becoming non-spherical. These soft or low tension windings are applied until they 90 make the ball hard enough to allow greater tension to be applied without distorting the ball, whereupon the tension on the thread 22 is increased. 95

In the present invention, as shown in Figs. 7, 14 and 15, this application or increasing of pressure is accomplished automatically when the initial windings have been built up to a determined diameter. This is accomplished in my invention by releasing the tension on the springs 103 during the early part of the winding. The release and application of this tension may be accomplished in any suitable manner under the control of the pointer 105 or other apparatus control by the position of the discs 20 and 21, but it is preferably accomplished by a pneumatic operating means. For this purpose the pneumatic control valve 117 is so positioned that its valve stem 118 is engaged and lifted by contact with the pointer 61. 110

When a ball is inserted between the plates 20 and 21 and the pointer 61 is, therefore, in its uppermost position as shown in dotted lines in Fig. 7, this position of the pointer 115 and of the disc 21 being indicated by B. The lifting of the valve stem 118 opens communication from an air pipe 119 to an air pipe 120 that leads to a small cylinder 121 adjacent the tensioning device 100 as indicated in 120

Fig. 15. The admission of air under pressure to the cylinder 121 displaces a piston 122 into engagement with a lever 123, swinging the latter outwardly towards the tension disc 100. The lever 123 engages a stem 124 extending axially through the tension drum 100 and which in turn engages through slots in the stem or rod 105 the washer 102, thus relieving the tension of the spring 103 from the tensioning drum 100.

The lever arm 123 is rigidly mounted on the rock shaft 125 on which is also rigidly mounted a lever arm 126 that engages a similar stem for the tensioning drum 101. This allows the tension spools 100 and 101 to revolve freely and with little or no friction. This in turn releases considerable tension from the thread 22, but not sufficient to permit the arm 95' to drop. However, when the center or ball 25 has attained a diameter sufficient to make the ball hard enough so that greater tension may be applied to the thread 22 without distorting the ball, the pointer 61 will have swung downwardly sufficiently to release the valve plunger 118 and close the valve 117. The supply of air is then shut off from the cylinder 121 and the piston 122 being sufficiently small, allows the air to leak out.

The spring 103, acting through the pin 124 and the arms 123 and 126, pushes the piston 122 back allowing the friction discs 102 to come into contact with the friction drums 100 and 101, thereby applying the correct tension to the thread 22 to give a hard, tightly wound ball. This initial winding thus takes the place of hand winding when a soft or paste center is employed.

In résumé, the operation is briefly as follows: To insert a center for the ball 25 the operator depresses the pedal 58, Figs. 2, 3 and 9, thereby rotating counter-clockwise the arm 60 and with it the arms 43, 45 and 53 of the double bell crank lever, Figs. 7, 8 and 9. Through the links 46 and 54 the arms 45 and 53, respectively, rotate the crank arm 47, shaft 48 and yoke 49 clockwise, and the crank 55, shaft 56 and yoke 57 counter-clockwise. The yokes 49 and 57 engage the shafts 30 and 32 through the thrust bearings 51 and 52 and thereby shift the shaft 30 to the left and shaft 32 to the right. The center of the ball 25 is then inserted between annular grooves 27 of the discs 20 and 21 carried by the shafts 30 and 31 respectively. The pedal 58 is then released whereupon the weight 41, Fig. 9, rotates the lever arms 43, 45, 53 and 60 clockwise and through the links 46 and 54 and the shafts 48 and 56 and yokes 49 and 57 shifts the shafts 30 and 32 toward each other thereby clamping or holding the ball 25 in the groove 27 between the plates 20 and 21 by pressure of the weight 41. A thread 22 is drawn from the spools 23, Figs. 1 and 2, thence through the tensioning devices 24, Figs. 1, 2, 13 and 14, to the ball 25,

the tension of the thread lifting the lever arm 95'.

The lifting of the outer end of the arm 95' opens the valve 85, Fig. 12, and permits air under pressure to flow from the air valve assembly 83 through the pipes 84 and 86 to the diaphragm chamber 89, Figs. 4, 6 and 12. The pressure shifts the diaphragm and with it the head 90 in such a direction as to move the clutch 78 which is geared to the shaft 75, 75 against the face of the gear 68 which is driven by a continuously running motor 63 through the chain 64, Fig. 3, gear 65, shaft 66 and gears 67 and 68. The shaft 75 is thereby placed in rotation and with it the gears 79, 80 keyed to it. The gears 79 and 80 mesh with the gears 81 and 82 respectively, keyed to the shafts 30 and 32, thereby causing the shafts 30 and 32 to rotate in the same direction. The gear ratios of the shafts 79, 81 and 80, 82 are different, however, so that the shafts 30 and 32 rotate at slightly different speeds. The plates 20 and 21 are, moreover, mounted slightly eccentrically relative to each other on the shafts 30 and 32 so that an irregular rotating movement is imparted to the ball 25 in addition to the winding movement. As the ball 25 increases in diameter it moves the shafts 30 and 32 apart against the pressure of the weight 41. When this displacement reaches a predetermined position the constant tilting of the shaft 48 rotates a mercoind switch 108 mounted on this shaft and closes an electric circuit, as shown in Fig. 12, through the wires 108 and 111 and through a heating element 106 over which the rubber thread 22 passes.

The heating of the element 106 severs the thread 22 thus stopping the further winding of the ball. It also releases the lifting tension on the arm 95' which thereupon falls, closing the valve 85 and shutting off the connection of the pipe 86 and diaphragm chamber 89 to the air pressure tanks, and opening the valve 93 which vents the pipe 86 and diaphragm chamber 89 to the atmosphere. The head 90, Fig. 6, is thereupon shifted outwardly by the springs 95 disengaging the clutch plate from the gear 68 and thus disconnecting the driving shaft 75 from the driving motor 63. The rotation of the ball 25 thereupon ceases and it may be removed by depressing the pedal 58 and inserting a new ball as described above.

The pointer 61 actuates the valve plunger 118 of Fig. 7 to open communication from the air pipe 119 through the pipe 120 to the cylinder 121 and to displace the plunger 122 and with it the friction washer 102, thereby relieving the tension from the friction drum 100. When the diameter of the ball increases sufficiently to swing the arm 61 and valve plunger 118 downwardly to close the valve 117 the supply of air is cut off from the cylinder 121 and, leaking therefrom, permits the

tension spring 103 to press the piston 122 reversely and bring the friction washer 102 into frictional engagement with the friction drums 100 and 101 respectively, thereby applying tension to the thread 122.

What I claim is:

1. A winding machine of the type described comprising a plurality of pairs of discs, the discs of each pair having complementary annular grooves to receive a ball being wound with thread, a common driving means for rotating said discs about their axes, means for resiliently pressing the discs of each pair towards each other, means individually controlled by the separation of the discs of each pair to disconnect said pair of discs from said driving means, means for supplying thread to said ball being wound between said discs, and means for automatically severing said thread when the discs become separated to a predetermined distance.

2. In a winding machine of the type described a pair of discs having complementary annular grooves to receive a ball to be wound, shafts for said discs to enable said discs to be rotated about the axes of said grooves, a common drive shaft for said discs, supporting shafts and driving gear, a clutch between said driving gear and said common drive shaft, pneumatic means to move said clutch into engaging position to engage said drive shaft to said driving gear, and a valve controlled by the separation of said discs to a predetermined distance to release the pressure to said pneumatic means and to thereby disengage said clutch.

3. In a winding machine of the type described a plurality of pairs of discs, the discs of each pair having complementary annular grooves to receive a ball to be wound, shafts in approximate alignment for supporting and rotating said discs on the axis of said grooves, an individual drive shaft for each of said pair of discs and its supporting and driving shafts, a common source of power, individual clutches between said source of power and the drive shafts of said pairs of discs, pneumatic means for clutching said drive shafts individually to said power source, and means to disengage said pneumatic means upon the separation of said discs to a predetermined distance.

4. In a winding machine of the type described a pair of discs having complementary annular grooves to receive a ball, shafts in approximate alignment for supporting and rotating said discs about the axes of said grooves, means for resiliently pressing said shafts and discs towards each other, thread supplying and tensioning means for thread to be wound on said ball, an electric heating element in contact with said thread passing towards said ball, and means actuated by the separation of said discs to a predetermined

distance to close an electric circuit through said heating means.

5. In a winding machine of the type described a pair of discs having complementary annular grooves, means for resiliently pressing said discs toward each other, means for rotating said discs about the axes of said grooves from a drive shaft, a pneumatically controlled clutch for clutching said drive shaft to a source of power, means for supplying thread under tension to a ball between said complementary annular grooves, a lever tilted by the tension of said thread, control valves for said pneumatic means actuated by the tilting of said lever, and means for automatically severing said thread when said discs become separated to a predetermined distance.

6. A winding apparatus of the type described which comprises a pair of discs having complementary annular ball holding grooves, approximately aligned shafts supporting said discs, shafts having yokes individually engaging the disc supporting shafts, a lever having crank arms connected to said yoke shafts to rotate said yoke shafts in opposite directions, a weight tending to rotate said lever and said yoke shafts in a direction to press said discs and disc supporting shafts toward each other, means to supply thread to a core held between said discs, an electric switch mounted on and rotatable with one of said yoke shafts, and a heating element adjacent said thread and in circuit with said switch whereby said heating element is heated sufficiently to sever said thread when said switch is closed.

7. In a winding machine of the type described, a pair of winding discs adapted to receive a ball center therebetween, means for rotating said discs to wind a thread upon said centers, and means actuated by the separation of said discs to a determined distance to apply tension to the thread being wound on said center.

8. In a winding machine of the type described a pair of winding discs adapted to receive a ball center between them, means for rotating said discs to wind a thread upon said centers, means for tensioning the thread supplied to said center and means for releasing the tension on said thread until said discs are separated to a determined distance.

9. In a winding machine of the type described a pair of discs having complementary annular grooves, the radial section of said grooves being in the form of a segment of a circle, and means for rotating said discs about the axes of their respective annular grooves and for supporting said discs with said axes slightly out of alignment and wholly within the inner periphery of the groove of the opposite disc and with the axes of said discs in fixed position.

10. In a winding machine of the type de-

scribed a pair of discs having complementary annular grooves, the radial section of said grooves being in the form of a segment of a circle; means for rotating said discs about the axes of their respective annular grooves and for supporting said discs with said axes out of alignment, and means for adjusting the distances between the axes of rotation of said discs.

10 In witness whereof I have hereunto signed my name.

CUYLER S. McCHESNEY.
